UNITED STATES PATENT OFFICE.

ALFRED C. BUTEHER, OF STAATSBURG, NEW YORK.

CURTAIN-POLE.

No. 927,109.

Specification of Letters Patent.

Patented July 6, 1909.

Application filed December 22, 1908. Serial No. 468,819.

To all whom it may concern:

Be it known that I, ALFRED C. BUTEHER, a citizen of the United States, residing at Staatsburg, in the county of Dutchess, State 5 of New York, have invented certain new and useful Improvements in Curtain-Poles; and I do hereby declare the following to be a full, clear, and exact description of the invention, such as will enable others skilled in the art to 10 which it appertains to make and use the same.

The invention relates to curtain poles and more particularly to the class of poles for supporting draperies, portières and the like.

15 The primary object of the invention is the provision of a pole of this character in which the curtains are loosely held suspended therefrom so as to permit them to be separated at varying distances from each other as the occasion 20 may demand.

Another object of the invention is the provision of a curtain pole in which the manner of connection of the curtains or draperies therewith is hidden from view and on which 25 curtains are permitted to be pulled apart or drawn together at will and which also will afford protection to the curtains to prevent the accumulation of dust at the point of their connection with the pole.

30 A further object of the invention is the provision of a curtain pole in which the curtains or draperies are readily and easily mounted in the pole and capable of being removed when deemed expedient.

35 A still further object of the invention is the provision of a curtain pole which is simple in construction, thoroughly efficient in operation and inexpensive in the manufacture.

With these and other objects in view the 40 invention consists in the construction, combination and arrangement of parts as will be hereinafter more fully described in detail, illustrated in the accompanying drawings which disclose the preferred form of embodiment 45 of the invention to enable those skilled in the art to practice the same, and as brought out in the claim hereunto appended.

In the drawings: Figure 1 is a front elevation 50 of a window showing the invention applied thereto. Fig. 2 is a longitudinal sectional view through the curtain pole. Fig. 3 is a bottom plan view of the curtain pole removed from the window. Fig. 4 is a sectional view on the line 4—4 of Fig. 3. Fig. 5 is a detail perspective view of the rod re-

moved from the pole. Fig. 6 is a sectional view on the line 6—6 of Fig. 3.

Similar characters indicate corresponding parts throughout the several views in the drawings.

In the drawings, the numeral 6 designates a pair of hangers or pole supporting brackets which are of the usual construction and mounted at the top of a window casement at opposite sides thereof, and in which is detachably received a curtain pole 7 which is of cylindrical contour throughout its longitudinal extent and is provided with a longitudinal bore 8 intersected by a slot 9 coextensive therewith and opening through the bottom of the pole. At a distance removed from opposite ends of the pole are reduced portions 10 in which are adapted to fit the hangers or brackets 6 when the pole is mounted therein or supported by the same 75 so as to prevent lateral displacement of the said pole when in operative position.

In communication with the bore 8 and leading through one end of the pole 7 is an opening 11 in which is adapted to be inserted 80 a removable rod 12 the latter formed at one end with a tapering threaded terminal 13 adapted to engage a threaded socket 14 at the closed end of the bore 8 in the pole and the opposite end of the rod 12 is formed with 85 a screw head 15 so as to permit the rod to be turned when connecting the threaded terminal 13 in the threaded socket in the closed end of the pole.

Formed integral with the pole 7 at one end 90 is a ball terminal 16 and at the opposite end of the said pole is mounted a removable ball head 17 which latter when mounted on the end of the pole is adapted to cover the screw head of the rod 15 and hide the same from 95 view.

Within the bore 8 of the pole 7 at a point centrally between the extremities of the bore is secured a stop eye 18 which latter is in alignment with the opening 11 and is adapted 100 to surround the rod 12 when inserted in the curtain pole. Surrounding the rod 12 on opposite sides of the stop eye 18 are a series of curtain rings 19 each of which is of less diameter than the interior circumference of the 105 bore 8 so that the same are hidden from view when the pole is mounted in operative position upon the window casing. Formed on and depending from the rings 19 are the usual eyes 20 for the attachment either by 110

stitching or otherwise of the curtains to the rings and which eyes are adapted to project through the slot 9 in the pole when the curtains or draperies are attached thereto. It is 5 obvious that the stop eye 18 will limit the movement of each series of rings 19 when shifted longitudinally on the rod 12 toward the center of the pole.

It is thought the foregoing description of 10 the pole will enable a clear understanding of the construction and operation thereof and therefore, a further description is deemed unnecessary.

What is claimed is—

15 A pole of the class described, comprising a cylindrical body having a bore centrally within the same throughout a greater portion of the length of the same, and intersected by a slot leading through the bottom of

the pole and coextensive with said bore, said 20 pole containing an opening in one end of the same and leading to the bore, a rod passed through said opening and having a threaded pointed end engaging the closed end of the pole, a screw head on the opposite end of the 25 rod, to permit the attachment of the rod in the pole, a removable terminal piece concealing the screw headed end of the rod and detachably mounted on the pole, a plurality of rings hung upon the rod, and having eyes 30 projecting through the slot and a stop loop encircling the rod at the center of the pole.

In testimony whereof, I affix my signature, in presence of two witnesses.

ALFRED C. BUTEHER.
